UNITED STATES PATENT OFFICE.

MARY V. BRUNK, OF KANSAS CITY, MISSOURI.

CAP, HAT, AND BONNET.

1,380,525.

Specification of Letters Patent. Patented June 7, 1921.

Application filed July 3, 1920. Serial No. 393,916.

To all whom it may concern:

Be it known that I, MARY V. BRUNK, a citizen of the United States, residing at Kansas City, in the county of Jackson and State 5 of Missouri, have invented certain new and useful Improvements in Caps, Hats, and Bonnets, of which the following is a specification.

My invention relates to improvements in 10 hats, caps and bonnets, for women and children, and my object is to provide articles of this character consisting of a plurality of parts which are detachably connected so that they can be taken apart and laundried.

15 Other objects will hereinafter appear, and in order that the invention may be fully understood, reference will now be had to the accompanying drawings, in which:

Figure 1 is a side elevation of a bonnet 20 made in accordance with the invention.

Fig. 2 is a plan view of the brim and the band of said bonnet.

Fig. 3 is a plan view of the crown of said bonnet.

25 Fig. 4 is a rear elevation of a modified form of hat or bonnet.

Fig. 5 is a plan view of the crown of said modified form.

Fig. 6 is a plan view of the brim and the 30 band of said modified form.

Fig. 7 is a front elevation of a modified form in the shape of a dust cap.

Fig. 8 is a plan view of the crown of said dust cap.

35 Fig. 9 is a plan view of the dust cap band.

Referring now more particularly to the form disclosed by Figs. 1 to 3, inclusive, 2 designates the one-piece crown capable of being flattened out and which consists of 40 flexible goods such as gingham, calico, etc. Said crown is cut out at each corner as indicated at 4 to form marginal flanges 6.

8 designates the one-piece brim capable of being flattened out and which consists, preferably, of some stiff fabric having sufficient body to insure the preservation of the shape of the complete bonnet. Said brim 8 has a front margin 10, side margins 12 and rear margins 14 with an intervening opening 16.

50 The brim 8 is provided adjacent to the rear margins 14 with suitable fastening devices, such for instance, as buttons 18 and sockets 20 whereby said rear margins 14 may be fastened together at the back of the bonnet.

55 The brim 8 is provided on its outer surface with a band 22, the ends of which terminate

adjacent to the rear margins 14, and like the same are provided with fastening elements 24 and 26. Said band 22 is secured to the brim 8 at four different places by suitable 60 means such as transverse stitches 28, leaving the rest of the band free so that the flanges 6 of the crown 2 may be passed through the spaces between the brim 8 and said band 22 and thus secure the crown 2 to 65 said brim 8.

When the bonnet is to be laundried the crown 2 is removed from the brim 8. The rear margins of the brim 8 and the band 22 are then unfastened, so that they may be 70 flattened out. After the parts are laundried they are again assembled by fastening the margins 14 of the brim 8 together. The ends of the band 22 are also secured together, after which the flanges 6 are passed 75 between the brim 8 and the band 22, the openings 4 coming opposite the stitches 28 as partly disclosed on Fig. 1. When the crown 2 is thus placed in position, it is reliably held upon the brim 8 by the flanges 6 80 and the band 22.

The modified form disclosed by Figs. 4 to 6, inclusive, is similar to the forms disclosed by Figs. 1 to 3, inclusive, as evidenced by corresponding reference numerals with exponents "e." The main difference resides in the crown 2^e, which does not have the marginal openings 4, but openings 4^e for the passage of the band 22^e. Said band 22^e is made in two pieces which are secured to the 90 brim 8^e by stitches 28^e. After this form has been laundried it is assembled by buttoning the rear margins 14^e together and passing each piece of the band 22^e through an opening 4^e in the crown 2^e, the margin of which 95 is held down upon the brim 8^e by the band 22^e when the two sections thereof are tied together at their ends as disclosed on Fig. 4.

In the modified form disclosed by Figs. 7 to 9, inclusive, a dust cap is shown in which the crown 2^a and the brim 8^a are combined in one piece as disclosed on Fig. 8. The brim 8^a is divided into four flanges 6^a by openings 4^a. A band 22^a is provided which consists of three continuous elements 22^b, 22^c 105 and 22^d. When the dust cap is to be laundried, the band 22^a is removed from the combined crown 2^a and brim 8^a, so that they may be flattened out. After being laundried the parts are assembled by passing the 110 flanges 6^a downwardly through the corresponding spaces 23 between the elements 22^a.

and 22^d, the openings 4^a coming opposite the stitches 28^a, which hold the elements 22^b, 22^c and 22^d together. The flanges 6^a are then folded upwardly through the openings 25 between the parts 22^b and 22^c.

From the foregoing it will be readily understood that the several pieces which form the article may be readily taken apart and washed, ironed out straight or flat, and then 10 again assembled.

Having thus described my invention, what I claim and desire to secure by Letters Patent, is:

- 15 1. An article of the character described, consisting of a crown made from one piece of material adapted to be flattened out, a brim separable from said crown and consisting of one piece of material adapted to be flattened out, and a band secured at intervals 20 to said brim to leave spaces for the passage of the margins of the crown so that the latter and the brim will be held in assembled position.
- 20 2. An article of the character described, 25 consisting of a one-piece crown adapted to be flattened out having flanges spaced apart

by openings in said crown, a one-piece brim separable from said crown and adapted to be flattened out, and a band secured at intervals to said brim to leave spaces for the passage 30 of the flanges which coact with the band in holding the brim and the crown in assembled position.

3. An article of the character described, 35 consisting of a one-piece crown capable of being flattened out, a one-piece brim separable from said crown and capable of being flattened out, said brim having two rear ends spaced apart by an intervening opening, means for detachably connecting said 40 rear ends, and a band secured at intervals to said brim to leave spaces for the passage of the margins of the crown so that the latter and the brim will be held in assembled position. 45

In testimony whereof I affix my signature in the presence of two witnesses.

MARY V. BRUNK.
